UNITED STATES PATENT OFFICE.

OTTO N. GREDELL, OF WINNWOOD, MISSOURI, ASSIGNOR TO SHEET METAL PRODUCTS COMPANY, OF KANSAS CITY, MISSOURI, A CORPORATION OF MISSOURI.

ACETYLENE GENERATOR.

1,411,084.

Specification of Letters Patent. Patented Mar. 28, 1922.

Application filed July 28, 1919. Serial No. 313,718.

To all whom it may concern:

Be it known that I, OTTO N. GREDELL, a citizen of the United States, residing at Winnwood, in the county of Clay and State 5 of Missouri, have invented a certain new and useful Improvement in Acetylene Generators, of which the following is a specification.

My invention relates to improvements in 10 acetylene generators.

One of the objects of my invention is to provide an acetylene generator with novel means for automatically regulating the feeding of the carbide.

15 My invention provides further an acetylene generator which is simple in construction, cheap to manufacture, not liable to get out of order, which is durable and reliable in operation and which is not liable to 20 clogging of the carbide feeding mechanism.

25 My invention provides further novel means of adjustment of the carbide feeding means by which the generator is adapted to operate under different pre-determined pressures.

My invention provides further novel float actuating means.

30 My invention provides still further a container for water and gas combined with a float chamber communicating therewith and novel means for regulating the amount of water held in the float chamber and the container.

35 The novel features of my invention are hereinafter fully described and claimed.

In the accompanying drawings, which illustrate the preferred embodiment of my invention,

40 Fig. 1 is a central vertical sectional view of my improved acetylene generator.

Fig. 2 is an enlarged vertical sectional view on the line 2—2 of Fig. 1.

Fig. 3 is an enlarged horizontal sectional view on the line 3—3 of Fig. 1.

45 Similar reference characters designate similar parts in the different views.

My improved construction provides a container adapted to hold water and gas and comprising, preferably, a vertical cylindrical body 1 having its upper end normally closed by a head 2, through which extend

bolts 3, which engage an annular member 4 encircling and secured to the body 1 and supporting a gasket 5, against which the head 2 bears.

55 The lower end of the body 1 is closed and is preferably mounted in a suitable supporting base 6. A clean-out conductor 7 containing a shut-off valve 8 connects to the bottom of the body 1.

60 Attached to the under side of the head 2 is a suitable carbide holder, preferably comprising a hopper 9 of funnel shape and provided in its lower end with a discharge opening 10, through which carbide contained in the hopper may be discharged downwardly into a body of water 11, which is held in the body 1.

65 For regulating the discharge of carbide through the opening 10, the hopper 9 has attached to it a tubular member 12, which encircles the opening 10 and to which are pivoted on horizontal pins 13, two inclined closure members 14, which are arranged to swing downwardly and away from each 75 other from the closed position shown in the drawing, by gravity.

70 For automatically forcing the closure members 14 toward the closed position as the pressure in the gas container rises, I provide novel float actuated means which will now be described.

75 Fig. 15 designates a vertically slidable member having at its lower end a vertical stem 16, which is slidably mounted in a horizontal 85 arm 17, which extends inwardly from the body 1. The member 15 is provided with two sets of arms 18 which respectively carry rollers 19, which bear against the under and outer sides of the closure members or 90 doors 14.

For lifting the member 15 toward the closing position, I provide a substantially horizontal lever 20, which at one end is provided with two arms 21, the upper sides 95 of which are adapted to respectively engage and lift two rollers 22 rotatably mounted on the member 15.

100 The lever support 20 is preferably mounted on a vertically adjustable fulcrum support comprising a horizontal pin 23, which is mounted in a member 24, in which is

rotatably mounted the lower end of a vertical screw 25, which carries the member 24 and which has its screw-threaded upper portion fitted in a nut 26, which is externally 5 screw-threaded and fitted in a threaded hole in the head 2. The nut 26 is mounted in a vertical tube 27 which extends from the top to the bottom of the hopper 9 and through which the screw 25 extends.

10 The upper end of the screw 25 is provided with a hand wheel 28, above the head 2, by means of which the screw 25 may be manually rotated in the proper direction for bodily lifting or lowering the lever 20, 15 through the intermediary of the member 24 and pin 23.

To prevent leakage of gas through the nut 26, the upper end of the nut is provided with an internally screw-threaded recess in which 20 is fitted a threaded packing ring 29, which encircles the screw 25 and bears against packing 30, mounted in said recess and bearing against the screw 25.

For automatically forcing downwardly the 25 left end of the lever 20, as viewed in Fig. 1, so as to move the lever toward the closing position, as the gas pressure increases, I provide a hollow float 31, preferably open at its lower end, but which may have a closed 30 lower end, and to the upper end of which are attached the arms of an inverted U-shaped yoke 32, the under side of the transverse portion of which rests upon a roller 33 carried at the left end of the lever 20, 35 as viewed in Fig. 1.

For lifting the float 31, as the gas pressure decreases, so as to permit the closure members 14 to move toward the open position, so that more carbide may be discharged into 40 the water 11, I provide a receptacle for liquid, preferably water, comprising an outer shell 34, which is closed at its lower end, and which is mounted in the container 1. Located within the shell 34 and spaced apart 45 therefrom so as to form an annular chamber 35, which is closed at its upper end, is a vertical tube 36, the lower end of which is spaced apart from the bottom of the shell 34, so as to permit liquid, such as water 37, 50 to pass from the chamber 38, which is formed by the tube 36, to the chamber 35. The upper end of the chamber 38 communicates with the interior of the container 1 above the level of the water 11. The float 55 31 is vertically movable in and spaced apart from the tube 36.

In order that the proper amount of water may be initially placed in the container 1 and in the chambers 38 and 35, the chamber 60 38 near its upper end is provided with a water inlet pipe 39 which, at the outer side of the container 1, is provided with a shut-off valve 40. The chamber 38 near its upper end is provided with an outlet pipe 41, 65 which extends through the shell 34.

The container 1, at a point lower than the outlet pipe 41 is provided with an outlet pipe 42, in which is mounted a shut-off valve 43.

In order that the two valves 40 and 43, 70 which are of the ordinary oscillatable type, may be simultaneously opened and closed, I provide a vertical rock shaft 44, which has its upper and lower ends respectively rigidly attached to the rotary valve 40 and 43, and 75 which is provided with a laterally extending handle 45.

By turning the handle 45 to the open position, both valves 40 and 43 will be opened, and water will flow through the inlet pipe 80 39 into the chamber 38. When the level of the water in the chamber 38 rises to the height of the outlet pipe 41, the water will be discharged through the outlet pipe 41 into the container 1. When water begins to 85 flow out of the container 1 through the outlet pipe 42, the handle 45 is turned so as to close the valves 40 and 43.

The head 2 of the container may be provided with a charging opening, through 90 which carbide may be placed into the hopper 9, and which is normally closed by a suitable cover 46, through which extends a bolt 47 having threaded engagement at its lower end with a closure plate 48 which 95 bears against a gasket 49, at the inner side of the head 2.

After the proper amount of water has been deposited in the chamber 38 and container 1, and a supply of carbide has been 100 placed in the hopper 9, the hand wheel 28 is turned so as to adjust the screw 25 to a position such that the lever 20 will permit the proper opening of the closure members 14 to correspond with the amount of pressure 105 which it is desired to have carried in the container 1.

The members 14 being open, will permit carbide to pass downwardly through the opening 10 of the hopper into the water 11, 110 thus generating gas, the pressure of which will be communicated from the container 1 to the top of the float 31 and to the surface of the water in the chamber 38, thereby forcing the water in the chamber 38 downwardly 115 and thence upwardly into the chamber 35, and also into the float 31, when the latter has an open bottom.

As the water in the chamber 38 lowers, the air in the chamber 35 will be compressed, 120 and the float 31 will fall, thus forcing down the left end of the lever 20, as viewed in Fig. 1, and raising the right end of said lever, so as to slide upwardly the member 15, thereby, 125 through the intermediary of the rollers 19 forcing the closure members 14 toward the closed position, thereby reducing the supply of carbide which is being deposited into the water 11. As the gas is withdrawn from the container 1 for use, the gas pressure will 130

lower, upon which the pressure of the air in the chamber 35 will force water therefrom into the chamber 38, thus lifting the float 31, which will permit the right end of the lever 20, as viewed in Fig. 1, to lower, upon which the closure member 14 will open wider to permit an increased discharge of carbide into the water 11.

If it is desired to accumulate a greater pressure of gas in the container 1, the hand wheel 28 is turned so as to lower the screw 25, thus lowering the lever 20.

To stir the carbide and to prevent its clogging as it passes between the closure members 14, there may be provided on the member 15 a plurality of vertical pins 50 which extend upwardly between the inner edges of the closure members 14.

By turning the screw 25 so as to lift it the proper distance, the closures 14 may be closed tightly so as to prevent any discharge of carbide, when it is desired to shut down the operation of the machine.

In order, however, that the operation of the machine may be shut down, without disturbing the proper operative adjustment of the screw 25, I provide additional manually operated means for closing the members 14 independently of the screw 25, lever 20 or float 31. Such additional means comprises a vertical screw 51, which is fitted in a nut 52, corresponding in construction to the nut 26 and similarly mounted in the head 2. The upper end of the screw 51 has secured to it a hand wheel 53, and the lower end of the screw 51 is rotatably fitted in a member 54, which the screw 51 supports and which is pivoted by a transverse pin 55 to a horizontally disposed lever 56 having two arms 57 which are respectively pivoted to two arms 58 extending laterally from the tubular member 12. The arms 57 are adapted to strike respectively shouldered portions 59, Fig. 2, provided at opposite sides respectively of the member 15 and which have respectively mounted in them vertical guide pins 60, slidably mounted in the member 13.

By turning the screw 51 so as to lift the right hand of the lever 56, the latter may be moved so as to lift the member 15 so as to close the members 14.

To prevent gas escaping, where the screw 51 extends through the head 2, the nut 52 may be provided with a packing collar 61, which bears against packing 62, mounted in the nut 52 around the screw 51. The screw 51 may extend through a vertical tube 63, which extends between the bottom of the hopper 9 and the head 2 and in the upper end of which the nut 52 is mounted. The nut 52 is externally screw-threaded and fitted in a threaded hole in the head 2.

Upon lowering the screw 51, the lever 56 may be lowered to permit the members

14 to open, upon which the production of gas will be automatically recommenced and continued in the manner already described.

By having the feed opening in the head, which is normally closed by the cover 46-48, communicating with the chamber above the hopper 9, carbide may be placed in the carbide holder without removing the head 2 and without disturbing any of the operating parts, the float 31 being located 75 below the carbide holder, as is the mechanism which controls the feed of the carbide from the holder.

I do not limit my invention to the structure shown and described, as modifications, within the scope of the appended claims, may be made without departing from the spirit of my invention.

What I claim is:-

1. In an acetylene generator, a container 85 adapted to hold water and gas, means for feeding carbide into the water, a lever, means actuated by the lever for controlling said feeding means, a vertically adjustable fulcrum support for the lever, and means 90 actuated by change of gas pressure in the container for swinging the lever.

2. In an acetylene generator, a container adapted to hold water and gas, means for feeding carbide into the water, a lever, 95 means actuated by the lever for controlling said feeding means, a vertically movable fulcrum support for the lever including two members, one a screw and the other a nut fitted on said screw, one of said members 100 being supported by said container, and means actuated by change of gas pressure in the container for swinging said lever.

3. In an acetylene generator, a container adapted to hold water and gas, means for 105 feeding carbide into the water, a lever, means actuated by the lever for controlling said feeding means, a receptacle for liquid having means by which change of gas pressure in the container effects vertical movement of the liquid, a float carried by said liquid engaging and adapted to swing said lever, and a vertically adjustable fulcrum support for the lever.

4. In an acetylene generator, a container 115 adapted to hold water and gas, means for feeding carbide into the water, a lever, a vertically adjustable fulcrum support for the lever, means actuated by the lever for controlling said feeding means, a receptacle 120 for liquid having two chambers, one of which communicates above the liquid with said container above the water in the latter and which communicates with the other chamber below the level of the liquid, and a 125 float carried by the liquid in one of said chambers and adapted to engage and swing said lever.

5. In an acetylene generator, a container 130 adapted to hold water and gas, a carbide

holder arranged to discharge carbide into the water, a closure for regulating such discharge, a lever, a vertically adjustable fulcrum support for the lever, means actuated by the lever for moving the closure toward the closed position, a float adapted to engage and swing said lever, and means actuated by change of gas pressure in the container for vertically moving said float.

10 6. In an acetylene generator, a container adapted to hold water and gas, a carbide holder arranged to discharge carbide into the water, a movable closure for regulating such discharge, a lever, means actuated by 15 the lever for moving said closure toward the closed position, a vertically adjustable fulcrum support for the lever, including a vertical rotatable screw, which when turned effects vertical adjustment of the 20 lever, a float engaging said lever and adapted when moving vertically in one direction to swing the lever toward the closed posi-

tion, and means actuated by change of gas pressure in said container for vertically moving said float.

25 7. In an acetylene generator, a container adapted to hold water and gas, a carbide holder arranged to discharge carbide into the water, a movable closure for regulating such discharge, a lever, a vertically adjustable fulcrum support for the lever, means actuated by the lever for moving said closure toward the closed position, a receptacle for liquid having two chambers, one of which communicates with said container above the liquid and above the water, and which communicates with the other below the level of the liquid and a float carried by the liquid in one of said chambers and arranged to engage and swing said lever 40 toward the closing position.

30 35 In testimony whereof I have signed my name to this specification.

OTTO N. GREDELL.
